ATTORNEY.

UNITED STATES PATENT OFFICE.

WILLIAM MARSHALL JEWELL AND OMAR HESTRIEN JEWELL, OF CHICAGO, ILLINOIS.

CAN OPENER.

Application filed May 19, 1924. Serial No. 714,422.

To all whom it may concern:

Be it known that we, WILLIAM MARSHALL JEWELL and OMAR HESTRIEN JEWELL, citizens of the United States, residing at Chicago, Ill., have invented certain new and useful Improvements in Can Openers, of which the following is a specification.

Our invention relates solely to the class of can openers employing cutting wheels (and particularly those of a portable construction for household use), and is intended primarily to lessen the cost of construction of the one shown in our copending application filed Dec. 31, 1923, Serial Number 683,723; but retaining the essential feature of spring tension or elasticity between the working parts.

In the device herein shown, the driving knurl wheel and the cutter wheel are placed at the opposite end of the handle or close to the bent portion instead of at the free ends of the U; in this way the two sides are used as squeezers to bring the wheels together and the flexibility of the handles thus formed affording sufficient pressure to cut through the can wall and most seams but yielding, should occasion require, to very heavy seams or obstructions liable to interfere with the turning of the driving wheel or injure the cutter wheel.

Figure 1 is a top view, illustrating the principal features of construction. Fig. 2 is a part cross section on line *c-c* of Fig. 1. Figures 3, 5, and 7 show some obvious modifications. Figures 4 and 6 are cross sections on lines *d-d* and *e-e* of Figures 3 and 5 respectively.

In Figure 1 the sides, or handles; 1 and 1^a are formed of one piece of spring steel bent in the shape of a U and twisted at right angles at the bend 2 and the intermediate points *b* to obtain suitable flexibility; the spring tension being inwardly so as to keep the handles closed when not in use. A flattened ring 3, or other suitable arrangement, may be used to obtain a uniform elastic pressure between the wheels and the can flange and to assist in closing the handles. The pin 4 prevents this ring from slipping off.

As will be seen in Fig. 2, the handles 1 and 1^a at points adjacent to the bend, carry the cutter wheel 5, shoulder screw 6 and nut 7; on one side, and the knurled driving wheel 8, stem 9, turning bar 10 on the other

side, respectively. The dotted lines 11 and 12 represent the top and side wall of the can, respectively.

In the modifications shown in Figs. 3 and 5, the handles 1 and 1^a are separate pieces; in Fig. 3 they are rigidly joined by a small piece of spring steel 13 riveted at 14, while in Fig. 5 a swinging joint is formed by turning over one end of the handle 1^a at right angle 15 and riveting to one end of the handle 1 at 16.

The construction shown in Fig. 7 is substantially the same as that of Fig. 1 with the exception of the use of wooden handles or extensions and round, instead of flat, spring steel. The round steel is flattened at *f* and *f* and drilled at 17 and 18 for the knurled driving wheel 8 and shoulder screw 6 respectively. The handles 1 and 1^a are round at 19 and checked down, as shown by dotted lines, where they enter the wood handles 20 which are reinforced by metal ferrules 21. The swinging point or bend 22 is also round and same diameter as at 19.

In Fig. 5, the flexible points *b* are elongated to form a curved handle, shown in part; and in Fig. 3 this result is attained by slotting as at points *g*, so that the handles will touch, or nearly touch, when the proper tension has been applied to the can flange.

What we believe to be new and desire to secure by Letters Patent is:

1. A portable can opener comprising two movable handles adapted to be held in one hand and joined adjacent to one end of each handle, a cutter wheel mounted on one of the handles and a driving wheel mounted on the other handle; both of said wheels being located adjacent to the closed ends and between the joint and the open extended ends.

2. A portable can opener comprising a U-shaped spring handle, a cutter wheel mounted on one side and a knurled driving wheel mounted on the other side of said handle adjacent to the bend.

3. A portable can opener comprising a spring handle in the form of a U, a cutter wheel mounted on one side and a toothed driving wheel mounted on the other side; both of said wheels being located adjacent to the bend and the open ends of the handle extended sufficiently to apply the necessary pressure between said wheels and the can by clasping in one hand.

4. A portable can opener comprising two movable handles pivoted at one end of each handle, a cutter wheel mounted adjacent to the closed end on one of the handles and a driving wheel mounted adjacent to the closed end on the other handle; both of said wheels being located between the pivot and the clasped ends.
5. A portable can opener comprising two movable handles united at one end of each handle, a cutter wheel and a driving wheel

mounted thereon in opposed relation to each other at the closed ends.

In testimony whereof we have affixed our signatures hereto this seventeenth day of 15 May, 1924.

OMAR HESTRIEN JEWELL.
WILLIAM MARSHALL JEWELL.
